D. J. SCOTT,
OFFSET PERFECTING PRESS,
APPLICATION FILED SEPT. 29, 1916.

1,273,004.

Patented July 16, 1918.

UNITED STATES PATENT OFFICE.

DAVID JOHN SCOTT, OF PLAINFIELD, NEW JERSEY, ASSIGNOR TO ISABELLA SCOTT AND
DAVID J. SCOTT, EXECUTORS OF WALTER SCOTT, DECEASED.

OFFSET PERFECTING-PRESS.

1,273,004.

Specification of Letters Patent. Patented July 16, 1918.

Application filed September 29, 1916. Serial No. 122,333.

To all whom it may concern:

Be it known that I, DAVID J. SCOTT, a citizen of the United States, and a resident of Plainfield, in the county of Union and State of New Jersey, have invented certain new and useful Improvements in Offset Perfecting-Presses, of which the following is a specification.

The present invention relates generally to offset perfecting presses and has more particularly reference to the general arrangement of the units composing such press.

The present application is in part a continuation of, and in part an improvement on, one filed April 2, 1915, Serial No. 18,639, and has for its main object to provide a machine in which both sides of the web are printed by the offset method without the omission of elements necessary to produce high class results, and, at the same time, to provide an arrangement of cylinders whereby all the working parts will be completely accessible. Another object of the invention is to provide means for conveniently controlling the various instrumentalities that make up the press.

Accordingly, the invention consists of the features of construction, combination of parts and arrangement of elements, herein-after described, a preferred form of which is disclosed in the accompanying drawings and description. However, changes may be made in the particular form herein described without departing from the legitimate and intended scope of the invention as defined in the appended claims.

In said drawings:

Figure 1 is a diagrammatic view showing a machine embodying the invention in elevation.

Fig. 2 is a detail view of the throw-off of the impression cylinder of the second unit and associated elements.

Similar characters of reference indicate corresponding parts in the several views.

In the preferred form shown in the drawings, A, C and E represent respectively the plate, blanket or transfer, and impression cylinders of one couple or unit, while B, D and F represent respectively the plate, blanket or transfer, and impression cylinders of the second printing couple or unit. It will be observed that the transfer and form-carrying cylinders are arranged one above the other, in the present case the form-

carrying cylinder being lowermost, and form an exposed operating side that is readily accessible to the operator for manipulation of the form and blanket members; and that the impression cylinder of each unit is offset (in this embodiment only partly) out of the vertical plane of the other cylinders of the unit and is therefore non-adjacent to the operating side. The two units are so grouped that the operating sides are outermost and the impression cylinders innermost and comparatively close together. The impression cylinders are here uppermost of the structure.

I is a source of the supply of paper in web form and L is a delivery, here conveniently represented as a former folder. These instrumentalities are located adjacent to the outer operating sides of the machine and spaced therefrom to afford room for platform or gangways G and H.

O indicates the usual inking mechanism and N water rollers, which may or may not be employed, that are located non-adjacent to the operating side of the machine.

37 is an anti-smutting device which engages with the impression cylinder of the second unit to prevent smutting of the cylinder by the previously printed side of the paper.

The paper is led from the source of supply I over guide rolls X', underneath gangway G and one unit or couple to a point intermediate the two units or couples, thence upwardly between the two units, thence over a guide roller X² to the impression cylinder of the other printing couple, thence to the impression cylinder of the first-mentioned printing couple; and thence above the impression cylinders of both printing couples over the guide roller X³ to former folder L.

It will be noted that the anti-smutting device 37 is located non-adjacent to the operating side of the unit with which it co-operates and that it is situated intermediate the two printing units.

Suitable means are provided for separating the elements composing the units so as to render the parts accessible for manipulation by the pressman. In the present instance, the transfer or blanket cylinders C and D are movable away from the other members comprising the unit and outwardly of the exposed operating side. The impression cylinders are likewise movable but inwardly.

toward each other away from their co-operating transfer cylinders. So likewise the dampening mechanisms, when such form a part of the structure, are movable toward each other and away from the form-carrying cylinders. As shown here, the dampening mechanisms are located non-adjacent to the operating side of the machine.

- Various instrumentalities may be employed for the purpose of effecting separation of the elements but in the preferred form, here disclosed, 53 indicates the shaft of impression cylinder F which is mounted in a rectangular sliding box 54. This sliding box carries a shaft 55 that forms one member of the toggle, the other member of which is a link 56. A block 57 is adjustable in the framing by means of an adjusting screw 58 and a locknut 58^a. On the end of shaft 55 is an operating lever 59 having secured at its outer end a connecting rod 60 extending to a bell crank 61. The cylinders E, D and C are similarly mounted and it is therefore unnecessary to describe in detail each mounting, it being sufficient to describe briefly the trip bell crank 61^a, 61^b and 61^c. Each bell crank is provided with a handle indicated respectively at 14, 28, 39 and 37'. Extending between bell crank 61 of impression cylinder F and bell crank 61^a of impression cylinder E is a rod 26 disconnectible from one of said bell cranks by reason of a hook 38. When the hook is in position, manipulation of either one of handles 14 or 28 will trip both of the impression cylinders toward each other and away from their complementary blanket cylinders. If hook 38 is disconnected, each impression cylinder may be tripped independently of the other. Similarly, there is a rod 120 which extends across the machine between bell cranks 61^b and 61^c of the two blanket cylinders. This rod likewise has a hook connection 36 at one end so that when in position manipulation of handles 39 or 37' will trip both blanket cylinders away from the plate and the impression cylinders outwardly of the operating sides of the machine and which, when disconnected, will permit each of said blanket cylinders to be tripped independently of the other.
- It will be noted that the web in passing around impression cylinder F is doubled back upon itself to form upper and lower web runs, as shown, and that the anti-smutting device 37 is located intermediate these two web runs. For the sake of convenience, this anti-smutting device 37 is mounted on a sliding box 54 so that when impression cylinder F is thrown off, the anti-smutting device will be moved bodily with it. There is also provided an eccentric 37^a by means of which one of the rolls of the anti-smutting device may be thrown off impression

cylinder F. The anti-smutting device here consists of a fountain 37^b with the usual fountain roller 37^c, a ductor roller 37^d and an anti-smutting roller 37^e. Preferably, oil is applied to the surface of cylinder F to prevent smutting. 70

The water rollers N are mounted in a carriage N' which may be moved toward and away from the form-carrying cylinders by means of handle 34. 75

What is claimed is:

1. A rotary offset perfecting machine comprising: a plurality of side-by-side units printing from positive forms on opposite sides of impression receiving material, each unit consisting of a form-carrying, a transfer and an impression cylinder all of substantially the same diameter, the form-carrying and transfer cylinders being arranged in an upright column and the impression cylinder being arranged out of line with the other cylinders and uppermost of said column to afford an exposed operating side for the unit, said units being grouped with their operating sides outermost and with their impression cylinders innermost, and an anti-smutting device, engaging with said impression cylinder of said second unit, located intermediate the two units. 85

2. A rotary offset perfecting machine comprising: a plurality of side-by-side units printing from positive forms on opposite sides of impression receiving material, each unit consisting of a form-carrying, a transfer and an impression cylinder all of substantially the same diameter, the form-carrying and transfer cylinders being arranged in an upright column and the impression cylinder being arranged out of line with the other cylinders and uppermost of said column to afford an exposed operating side for the unit, said units being grouped with their operating sides outermost and with their impression cylinders innermost, an anti-smutting device, engaging with said impression cylinder of said second unit, located intermediate the two units, and means for moving the transfer cylinder of each unit outwardly with respect to the operating side of said unit and away from the other cylinders 100 of the unit. 105

3. A rotary offset perfecting machine comprising: a plurality of side-by-side units printing from positive forms on opposite sides of impression receiving material, each unit consisting of a form-carrying, a transfer and an impression cylinder all of substantially the same diameter, the form-carrying and transfer cylinders being arranged in an upright column and the impression cylinder being arranged out of line with the other cylinders and uppermost of said column to afford an exposed operating side for the unit, said units being grouped with their operating sides outermost and with their im- 120 125 130

- pression cylinders innermost, means for guiding the web below one unit, thence between the two units, thence to the impression cylinder of one unit, thence across from one unit to the impression cylinder of the other unit and thence up and around the said first unit, and an anti-smutting device, engaging with said impression cylinder of said second unit, located intermediate the two units.
- 5 4. A rotary offset perfecting machine comprising: a plurality of side-by-side units printing from positive forms on opposite sides of impression receiving material, each unit consisting of a form-carrying, a transfer and an impression cylinder all of substantially the same diameter, the form-carrying and transfer cylinders being arranged in an upright column and the impression cylinder being arranged out of line with the other cylinders and uppermost of said column to afford an exposed operating side for the unit, said units being grouped with their operating sides outermost and with their impression cylinders innermost, means for guiding the web between the two units, thence between the transfer and impression cylinders of the first unit, thence across from one unit to and between the transfer and impression cylinders of the second unit and thence above the impression cylinders of both units, and an anti-smutting device engaging with the impression cylinder of the
- 10 second unit and located above the web run between the two units and below the web run above the impression cylinders of the two units.
5. An offset web perfecting machine comprising: a plurality of units, each unit including a form-carrying, a transfer and an impression cylinder, means for bodily moving the impression cylinder of the second unit away from its transfer cylinder, and an anti-smutting device engaging the impression cylinder of the second unit and mounted to move bodily with said impression cylinder.
- 15 6. An offset web perfecting machine comprising: a plurality of units, each unit including a form-carrying, a transfer and an impression cylinder, means for bodily moving the impression cylinder of the second unit away from its transfer cylinder, an anti-smutting device engaging the impression cylinder of the second unit and mounted to move bodily with said impression cylinder, and means for throwing the anti-smutting device off said impression cylinder.
- 20 Signed at Plainfield, in the county of Union and State of New Jersey, this 27th day of September, A. D. 1916.
